CIRCUIT MAKER AND BREAKER FOR INTERNAL COMBUSTION ENGINES

Filed Nov. 28, 1921

UNITED STATES PATENT OFFICE.

JESSE T. GENTRY, OF VENTURA, CALIFORNIA.

CIRCUIT MAKER AND BREAKER FOR INTERNAL-COMBUSTION ENGINES.

Application filed November 28, 1921. Serial No. 518,148.

To all whom it may concern:

Be it known that I, JESSE T. GENTRY, a citizen of the United States, residing at Ventura, in the county of Ventura and State of California, have invented a new and useful Circuit Maker and Breaker for Internal-Combustion Engines, of which the following is a specification.

This invention relates to means for intermittently energizing the spark plugs of a multiple cylinder engine and an object of the invention is to provide simple means whereby the actuating of the spark plugs is effectively accomplished.

An object of this invention is to simplify the ignition system of Ford cars. In cars of this character there are four cylinders and four vibrating coils connected respectively to the spark plugs in each individual cylinder and an object of this invention is to eliminate the use of coils and to simplify the Ford ignition.

The invention is applicable to an engine having any number of cylinders and spark plugs but an illustration of the same as applied to a four cylinder car will be sufficient for a full understanding of the invention.

Other objects, advantages and features of invention may appear from the accompanying drawing, the subjoined detail description and the appended claims.

The accompanying drawings illustrate the invention.

Figure 1 is a diagram illustrating the electrical connections in a device constructed in accordance with this invention.

Fig. 2 is a sectional elevation on line x^2 , Figs. 1, 3 and 4.

Fig. 3 is an end elevation of the distributor.

Fig. 4 is a section on line x^4 , Fig. 2.

Fig. 5 is a section on a reduced scale, on line x^5 , Fig. 1.

a indicates the primary and *b* the secondary leads to the coil box *c* connected by the lead *d* with the magneto, not shown.

1, 2, 4, 3 indicate the primary contacts all connected with the primary lead *a*, these contacts are shown connected together by the wire 5 and are in fixed relation to each other in a housing 6 of non-conducting material. Said housing also carries in fixed relation to each other and to the primary contacts 1, 2, 4, 3, the secondary contacts 1^a, 2^a, 4^a, and 3^a, and also a third set of con-

tacts 1^b, 2^b, 4^b, 3^b, respectively connected through plugs 1^c, 2^c, 4^c, and 3^c, and their leads 1^d, 2^d, 4^d, and 3^d, to spark plugs 1^e, 2^e, 4^e, and 3^e, for the several cylinders of the engine.

The distributor comprises a brush holder 7 having a socket 8 to set on the cam shaft 9 to which the brush holder is secured by suitable means as the set screw 10. Screw 10 is insulated by plug 10'. Said brush holder 65 carries the three brushes 11, 12 and 13. The brush 11 making a connection between the primary winding of the coil and the cam shaft 9 which serves as a ground to connect up the circuit.

The connection between the brush 11 and the cam shaft 9 includes a spring 14 set in a brass sleeve 15 that is in contact with the brass sleeve 16 which alines with the socket 8 and is fixed to the end of the cam shaft 9. 75 Three brushes 11, 12 and 13 are practically of the same construction including the brush proper of carbon or steel, the spring 14 and the sleeve 15. This construction of brush, however, may be varied within the judgment 80 of the constructor. The brushes 11, 12 and 13 are arranged respectively to travel in different paths and brush 11 is adapted to contact successively with the primary contacts 1, 2, 4, 3, in the order just stated, at 85 each revolution of the cam shaft and the brush carrier. The brushes 11, 12 and 13 are arranged in a common plane radial to the cam shaft 9 and the contacts in the housing as 1, 1^a, and 1^b, and are adapted to a common 90 radius so that as the brush holder revolves and brings the brush 11 into contact with primary contact 1 the brush 12 will contact with the secondary contact 1^a, and the brush 13 will contact with the spark lead 1^b as 95 shown by full line Fig. 1 to cause a spark in the spark plug connected to the plug 1^c, or as indicated by dotted position of the brushes to cause a spark in the spark plug connected to plug 14^c through contact 4, 4^a and 4^b and at each revolution of the distributor 7 a current will be successively directed through the 100 plugs connected as above stated.

The contacts 1^a, 2^a, 4^a, and 3^a are connected by wire 5^a that is connected by wire 6^a to 105 a socket 7^a for the plug of the secondary wire *b*.

The brush holder and the housing are preferably made of an electrical insulating substance such as fiber or other non-conduct-

60

70

ing compositions known on the market. The contact points are preferably segments made of brass and embedded in the insulating compositions, the intervening portions 17, 5 18 and 19 of which respectively constitute means for insulating the segments from each other.

The housing 6 has a cylindrical extension 20 that fits into a socket 21 in an engine 10 crank case 22, and it is held therein by means of an arm 23 that has one end attached by stud bolt 24 to the crank case, and the other end of the arm 23 is provided with a set screw 25 that has a bearing end 15 26 fitting loosely into the socket 27 in the housing 6, by which means the housing 6 can be rotated in the socket 21 for retarding or advancing the spark by means of the crank arm 28 and its usual connection to the 20 spark lever on a steering post of a vehicle.

Any practical source of electrical energy may be connected by wire *e* to coil box *c* and may comprise a magneto or battery or both, as is well known in the art.

25 I claim:

1. A circuit maker and breaker for ignition systems comprising primary contacts; said primary contacts electrically connected; secondary contacts of corresponding number, electrically connected; a set of lead contacts electrically connected corresponding in number and arrangement to the primary and secondary contacts; means insulating the contact faces of the primary contacts 30 from each other; means insulating the contact faces of the secondary contacts from each other; means insulating the lead contacts from each other; a brush holder provided with a brush connected with the ground and adapted to contact with the primary contacts respectively as the brush holder revolves; a second brush arranged to contact with the secondary contact as the brush holder revolves; and a third brush 35 electrically connected with the second brush and arranged to contact with the lead contacts respectively, as the brush holder revolves; said contacts being arranged in sets including secondary and lead contacts, and 40 the brushes being arranged to simultaneously and successively engage their respective contacts as the brush holder revolves.

2. A circuit maker and breaker for an internal combustion engine comprising a non-conducting cylindrical housing having an open end that is adapted to be fitted over the timer end of an engine shaft; a closed end to said housing, said closed end having an interior recess that is arranged central 45 to the axis of the timer shaft; primary contacts in the recess of said end wall electrically connected together and arranged to have a contact face thereof exposed toward the open end of said housing; secondary contacts arranged in the end wall and elec-

trically connected together said secondary contacts having contact faces exposed toward the open end of said housing; lead contacts in the annular wall that are arranged to expose a contact face toward the 70 axis of the timer shaft; a brush holder secured to the timer shaft; and spring pressed brushes arranged in said brush holder in position to engage said contacts when the timer is revolved.

3. A circuit maker and breaker for internal combustion engines comprising a non-conducting housing having primary contacts therein that are electrically connected; secondary contacts in said housing that correspond in number to said primary contacts and that are electrically connected and insulated from the primary contacts; a set of lead contacts in said housing corresponding in number to the primary and to the secondary contacts respectively and each connected to its respective secondary contact; and means for making and breaking contact in the primary circuit to cause flow of current through the secondary contacts to the 85 lead contacts substantially as described.

4. A circuit maker and breaker for internal combustion engines comprising a non-conducting housing; primary contacts in said housing that are electrically connected and also connected to the wiring of the primary circuit; secondary contacts in said housing that correspond in number to said primary contacts and that are electrically connected and that are insulated from the 90 primary contacts; a set of lead contacts in said housing corresponding in number to the primary and to the secondary contacts and spaced equidistant apart in said housing; means for making and breaking contact of the primary circuit to cause flow of current through the secondary contacts to the lead contacts; and means for moving said housing on its axis substantially as described.

5. A circuit maker and breaker for internal combustion engines comprising a shaft; a non-conducting housing loosely supported adjacent an end of said shaft; primary contacts in said housing that are arranged 115 equidistant apart and connected together by wires embedded in said housing, said primary contacts arranged in a primary circuit; secondary contacts in said housing that correspond in number to said primary contacts and that are connected together by 120 wires embedded in said housing and arranged in a secondary circuit and that are insulated from the primary contacts; a set of lead contacts in said housing corresponding in number to the primary and to the secondary contacts respectively and each in circuit with its respective secondary contact; brushes for engaging said primary contacts to interrupt the primary circuit; and 125 130

means for moving said housing to advance or retard the spark relative to increased or decreased engine speed.

6. A circuit maker and breaker for internal combustion engines comprising in combination with an engine casing having an annular hollow flange; a non-conducting housing, said housing having an annular flange revolvably fitted into the annular flange of said casing; means for holding said housing flange in said casing flange adjacent the timer end of said shaft; primary contacts in said housing that are electrically connected; and spaced equidistant apart and arranged radially around the axis of said housing and adjacent the timer end of said shaft; secondary contacts in said housing that correspond in number to said primary contacts and that are spaced an equidistance apart and arranged in the same axial planes but of greater radial distance from the axis of said housing than the primary contacts and are offset therefrom, said secondary contacts electrically connected; a set of lead contacts in said housing corresponding in number to said primary contacts and being spaced an equidistance apart and arranged in the same axial planes but of greater radial distance from the axis of said housing than the primary and secondary contacts and are offset therefrom, said set of lead contacts electrically connected; a revolvable insulated brush holder adapted to be secured on the timer end of an engine cam shaft; and spring pressed brushes in said brush holder that are arranged to engage said contacts as described.

In testimony whereof, I have hereunto set my hand at Los Angeles, California, this 21st day of November, 1921.

JESSE T. GENTRY.

Witness:

JAMES R. TOWNSEND.
